UNITED STATES PATENT OFFICE

EDWARD E. WHITMORE, OF CHICAGO, ILLINOIS, ASSIGNOR TO THE CURTAIN SUPPLY COMPANY, OF NEWARK, NEW JERSEY, A CORPORATION OF NEW JERSEY.

HOOD FOR CAR-DIAPHRAGMS.

1,078,757.

Specification of Letters Patent.

Patented Nov. 18, 1913.

Application filed February 10, 1913. Serial No. 747,826.

To all whom it may concern:

Be it known that I, EDWARD E. WHITMORE, a citizen of the United States, residing at Chicago, in the county of Cook and State 5 of Illinois, have invented certain new and useful Improvements in Hoods for Car-Diaphragms, of which the following is a specification.

In railway car construction, as is well 10 known, the vestibules of adjacent cars are closed in by a flexible diaphragm arranged at the two sides of and above the platform, this diaphragm being of the accordion type and connected at one extremity to the end of its 15 car and at the other extremity to a face plate which yieldingly bears against the face plate of the other car. By reason of the formation of the diaphragm in accordion plaits the upper roof portion of the same 20 presents creases or folds with sharp angles which coincide with the line of junction or hinge of the fabric and the dust and cinders collecting therein speedily cut and ruin the diaphragm.

25 This invention has for its object to overcome this trouble by the provision of a hood or fly overlying and in spaced relation to the roof of the diaphragm, the hood being formed with rounded grooves and down- 30 turned at the two sides of the vestibule to guard against the entrance of cinders and gusts of air thereunder.

In the accompanying drawings and in the 35 following description based thereon is set forth a preferred embodiment of the invention which is likewise susceptible of considerable variation as to constructional details without departure from the essence thereof or sacrifice of its material advantages.

40 In these drawings: Figure 1 is a vertical longitudinal section through the upper portion of a car vestibule; Fig. 2 is a partial transverse section on the line 2—2 of Fig. 1; Fig. 3 is a view partially in section and 45 partially in plan on the line 3—3 of Fig. 1; Fig. 4 is a perspective view of the diaphragm hood disassociated from the car; and Fig. 5 is a plan view of the blank from which such a hood is made.

50 Having reference in detail to the drawings, the reference numeral 11 designates generally the end of a car and the numeral 12 the face plate yieldingly supported by means of the spring 13, and the guide rod 55 14 playing within the aperture 15 of the

car end. The diaphragm is composed in the usual manner of the sections 16, 16 arranged in folds with their meeting edges united by the cover strips 17, the one extremity 18 of the diaphragm being secured to the car end 60 and the other extremity 19 being secured to the face plate 12.

The construction thus far described represents the usual form of car diaphragm and it is open to the objection that the dust 65 and cinders collect in the V-shaped troughs 20, 20 of the roof portion and working in between the meeting edges of the sections where seamed together, cut and thus ruin the fabric. Moisture likewise from snow 70 and rain finds its way into the seams and carrying with it the dust and grime acts destructively upon the diaphragm.

According to my invention a hood is formed from a blank 21 of the general shape 75 indicated in Fig. 5, which is clamped along its marginal edges 22, 22, between the retaining strips 23, 23 and the extremities 18 and 19 of the diaphragm proper, the whole being securely attached to the end of the car 80 and to the face plate by the fastening devices 24, 24. The blank is creased along two or more lines 25, 25 to provide the upturned margins 22, 22 by which it is secured to the car end and face plate, and along one or 85 more medial lines 26 to form an upstanding ridge which overlies the upstanding edges of the diaphragm folds. When thus creased the hood overlies the diaphragm in spaced relation thereto after the manner of the fly 90 of a tent. That portion of a hood between the creases 25 and 26 being formed as grooves having rounded bottoms 27, 27, as distinguished from the sharp tapered bottom of the angular spaces 20 of the diaphragm. The blank is provided in each of 95 its two sides with one or more notches 28, the adjacent edges of which are united as indicated at 29 to form a dart whereby the sides are drawn downward and inward toward the side walls of the diaphragm to give 100 a hooded effect and to more effectively exclude the dust and cinders as well as gusts of air from entering beneath the hood and lodging upon the diaphragm or by their violence turning the hood inside out or tearing it from its fastenings. By the provision of the darts 29 the lateral margins of the hood are very effectually stiffened while at the same time leaving them entirely flexible and 110

subject to collapse as the face plates yield under buffing strain.

I claim:

1. The combination with a car-diaphragm, of a hood disposed thereabove in spaced relation thereto, the hood having transversely extending grooves, and the outer terminal portions downturned toward the diaphragm, substantially as described.
2. The combination with a car-diaphragm, of a hood secured thereabove to the car end and face plate, the hood having transversely extending grooves with rounded bottoms and downwardly inclined toward the sides, the outer terminal portions downturned toward the diaphragm, substantially as described.
3. The combination with a car diaphragm, of a hood disposed thereabove, the hood having transversely extending grooves and downwardly inclined toward the sides, the

outer terminal portions provided between the grooves with darts whereby to deflect the same downwardly along the side walls of the diaphragm and prevent the entrance of 25 the elements thereunder, substantially as described.

4. The combination with a car-diaphragm, of a hood secured thereabove to the car end and face plate, the hood having transversely 30 extending grooves with rounded bottoms downwardly inclined toward the sides, the outer terminal portions provided between the grooves with darts whereby to deflect the same downwardly along the side 35 walls of the diaphragm and prevent the entrance of the elements thereunder, substantially as described.

EDWARD E. WHITMORE.
